TRACER FOR PROFILING MACHINES

Manuel Turchan, Dearborn, Mich.

Application April 1, 1938, Serial No. 199,482

1 Claim. (Cl. 90—62)

The present invention relates to tracers for pattern controlled hydraulically actuated duplicating machines.

Among the objects of the invention is a tracer which shall be relatively simple in construction but sensitive to minute variations in the surface of the pattern and active to cause cutter movement to reproduce such variations.

Another object is a tracer suitable for use in either horizontal or vertical machines with minor alteration.

Another object is a tracer of the type indicated in which the fluid flow is controlled by a valve which is subjected only to balanced pressures and therefore moves with a minimum tendency to jam.

Still other objects and advantages will be apparent from reference to the following description and the accompanying drawings in which

Figure 1 is a view in elevation of one form of a duplicating machine showing one method of use of the tracer.

Figure 2 is an enlarged vertical section through one form of the tracer.

Figure 3 is a vertical section of another form of the tracer.

Figure 4 is a plan view of a detail of the construction of Figure 3.

Figure 5 is a perspective view of another detail of the construction of Figure 3.

Referring now to the drawings, there is shown in Figure 1 a duplicating machine comprising a vertical spindle milling machine consisting of a standard 10 upon which is mounted a work table 11 arranged for horizontal and vertical movements. In the present instance, the horizontal movement of table 11 is accompanied by the conventional gearing, worms, etc., (details of which are not shown), while the vertical shifting movement is accomplished by hydraulic means shown as cylinders 12 supplied with pressure fluid through the pipes 13 and 14 which lead through the tracer 15 from a pump enclosed within tank 16 and driven by motor 17. The downward movement is accomplished by allowing the fluid from the lower part of cylinder 12 to exhaust through pipe 13, the tracer 15 and pipe 18, back to the tank 16 while at the same time the same pump causes flow of fluid under a lesser degree of pressure through pipe 19 to the upper part of the cylinder 12.

The standard or frame 10 of the machine also carries the cutter spindle 20 and means for rotating and in addition, at its upper part carries

a laterally projecting arm 21 upon which is mounted the tracer 15.

In operating such a machine, a pattern 25 and a roughly shaped work piece 26 are secured to the work table 11, the former occupying the same relative position to tracer 15 as the latter occupies to cutter 27.

With the pattern and workpiece in position and with the pump operating, when the table 11 is moved horizontally, contact of the tracer with the pattern will control the hydraulically produced vertical movement. As indicated above, this control is through valve means actuated by the tracer finger to regulate or cut off flow of fluid to or from the lower part of cylinders 12.

A simple form of the tracer controlling element is shown in Figure 2, which shows a cylindrical casing formed of a lower spindle supporting section 130, having a passage therethrough for the spindle 131, the passage being sufficiently large to permit a small lateral movement of the spindle and being surrounded by an inwardly projecting conical portion 130a, while the spindle 131 is provided with a mating conical flange 131a adapted to rest upon the part 130a with interposed antifriction balls 130b, maintained in their proper location by a suitable cage 131b.

The upper end of spindle 131 is also provided with a cone shaped flange 140 opening upwardly for a purpose to be described. Fixed upon the upper end of section 130 is a cylindrical valve member 145 provided with three internal peripheral grooves 149a, 149b and 149c having ports leading to the three conduits 14, 15 and 18 respectively.

Within the part 145 is a second valve member 160 in the form of a cylindrical member having a web 161 provided with a conical portion shaped to nest into the part 140 of the spindle with interposed antifriction balls 162 maintained in their proper location by a suitable cage 163. This valve member 160 is provided with two circumferential grooves 60a and 60b separated by a rib slightly less in width than the groove 149b in member 145. Valve member 160 is maintained in its relation to the spindle 131 by means of a spring 170 acting between it and a suitable adjusting screw 172 located in a cover member 173 shown as fixed in the top of member 145.

The operation of the tracer is as follows: When the tracer point member strikes an obstruction tending to move it either laterally or upward, either motion of the finger will cause the spindle to move the valve member 160 up-

wardly due to the conical members 130a, 131a, 140 and web 161.

In the position shown, since the rib between grooves 60a and 60b is slightly narrower than groove 149b, pressure fluid from the pump through conduit 14 will pass into the several grooves 149a, 60a, 149b, 60b, 149c, in order, and then out through conduit 18 to the tank.

When, however, the valve 160 is moved upward, flow from groove 60a to groove 149b is cut off and fluid already in the cylinder flows back through 60b to 149c and to conduit 18 and to the tank. If on the other hand, the point 132 drops free or starts to move away from an obstruction, the valve 160 will drop below the position shown and open communication between conduit 14 from the pump to groove 149b and conduit 13 leading to the cylinders 12.

This arrangement of the tracer and conduits provides a control suitable for a machine set-up as indicated in Figure 1. If, however, it is desired to have the tracer and cutter move to and from the work, the pressure fluid should be supplied to conduit 18 and the drain should be from conduit 14.

Another and preferred form of tracer is shown in Figures 3, 4 and 5.

The tracer construction as shown in Figures 3, 4 and 5 shows the tracer as consisting of a body 30 having axially arranged therein a spindle 31 of sufficient length to extend some distance from the lower end of said body, the free end being provided with means for attaching a pattern contacting piece 32 of substantially the same dimensions as the cutter 21. At substantially the lower end of the body 30, the spindle is mounted in an antifriction bearing 33 so constructed as to permit the spindle to swing about a center which coincides with the center of the bearing 33, while the spindle is supported by a shoulder 34 resting upon the bearing. At its upper end, the spindle is provided with an accurately centered conical member 40 and below this conical member with an oil shield 41, the purpose of which is explained later.

At the top of body 30 is fixed a cylindrical valve member 45 shown in detail in Figure 5. As indicated, this consists of a cylinder having near its upper and lower ends, peripheral grooves 46 and 47 respectively, each provided with a plurality of narrow passages 46a and 47a passing through the wall of the cylinder to the inside thereof. And each of the grooves 46 and 47 is also provided with one or more lateral enlargements or bays 46b and 47b respectively, near the extreme end of which is a through passage 46c and 47c respectively.

Further, between the grooves 46 and 47 and between bay 46b and 47b the cylinder is provided with a chamber 48, not in communication with either groove but having passages 48a and 48b through the cylinder wall at the top and bottom respectively, of the chamber.

It should be noted that all of the passages 47a are in alignment and the same is true of the 65 passages 46a. It should also be noted that passages 48a and 48b are located one on either side of the line of passages 46c and 47c. Further, each of the several lines of passages opens into an internal narrow groove of which there are 70 six, 49a, 49b, 49c, 49d, 49e, and 49f.

This member 45 is conveniently fixed to the top of body 30 although it may be integral therewith, if desired, and surrounding it is a cover member 50 for the grooves 46 and 47 and for

chamber 48, which member is provided with three passages, 51, 52 and 53, communicating with groove 46, chamber 48 and groove 47 respectively.

Within the member 45 and arranged with a close sliding fit is a movable valve member 60 provided with four peripheral grooves 60a, 60b, 60c, and 60d, each of about twice the width of one of the through passages and inner grooves in member 45.

This valve member 60 is provided with a web 61 having a downwardly directed conical portion of the same angularity as the cone 40 on the spindle and nesting therein with interposed anti-friction balls 62, a suitable spacer or cage 63 being used to maintain the balls in proper location.

If the tracer is to be used in a vertical position as indicated in Figures 1 and 2, it is desirable in addition to the parts already described, to add within the body 30 a suitable weight supporting spring 65 which is shown as acting between a suitable abutment such as the pin or plate 66 fixed to the spindle 31 and a thrust bearing 67 carried in the lower end of body 30.

If the tracer is to be used in a horizontal position, it is necessary to provide means holding the spindle and valve member 60 together. In such cases, a light spring 70 is used on top of valve member 60 and this is conveniently mounted upon a guide rod 71 threaded into member 60 and passing out through an adjusting screw 72 in the cover member 73.

In the construction of the valve members 60 and 45, the small interior grooves 49a and 49d have the same function as the groove 149a in Figure 2, while grooves 49b and 49e have the same function as groove 149b of Figure 2 and grooves 49c and 49f function like groove 149c of Figure 2, these several grooves being connected in pairs as stated, by the bays 46b, 47b and chamber 48.

In this figure (Fig. 3) the conduit 14 will be connected to passage 52, the conduit 13 to passage 51 and the conduit 18 to passage 53.

This construction functions in exactly the same fashion as the somewhat simpler construction of Figure 5, but since the several grooves and channels are connected at a plurality of points around the periphery of the valve members, the pressure will be equalized and all unbalanced side pressures eliminated.

Since the tracer of Figure 3 is designed primarily for use in machines in which the cutter and tracer move to and from the work and pattern, the pressure fluid will ordinarily be supplied to passage 53 and the exhaust will be from passage 51. In such mounting the rod 71 furnishes a convenient hand control to cause the tracer and cutter to move away from their contacts. If this movement is desired, the rod 71 is lifted to move the valve 60 upwardly. This of course closes the grooves connected to passage 52 and allows the pressure fluid free passage from the passage 53 to the passage 51 and to the cylinders which move the tracer and cutter.

In the vertical mounting of the tracer, as shown in Figure 3, any fluid escaping from between the valve members is prevented from running down the spindle by the shield 41 from which it drips into the trough 41a and is drained out through a passage 41b. Such draining is accomplished in the form shown in Fig. 2 through the action of member 131a and drain 141.

What I claim is:

A tracer actuated fluid control device for pro-

fitting machines having a pilot and mechanically operated means for moving the work and cutter relatively in one direction and hydraulically operated means for moving said parts relatively in a direction at right angles to the first movement, said control device consisting of a pilot carrying spindle, a shell into which said spindle extends, said shell being provided with a plurality of independent internal peripheral grooves and with independent external peripheral grooves each communicating with a group of said internal grooves, an outer shell surrounding said first

shell and forming a cover for the outer grooves and having separate passages leading thereto, a valve member slidable in said first shell and provided with peripheral grooves wider and less 5 in number than the aforementioned inner grooves, and means operatively connecting said valve member and spindle whereby displacing movement of the latter will cause movement of said valve member to cause the grooves therein 10 to provide communication between different groups of said inner grooves.

MANUEL TURCHAN.
